UNITED STATES PATENT OFFICE.

BENJAMIN WEISS, OF NEW YORK, N. Y.

FOLDING COUCH-BED.

1,300,069.

Specification of Letters Patent.

Patented Apr. 8, 1919.

Application filed February 3, 1917. Serial No. 146,312.

To all whom it may concern:

Be it known that I, BENJAMIN WEISS, a citizen of the United States, residing in the borough of Manhattan, in the county of New York, city of New York, and State of New York, have invented certain new and useful Improvements in Folding Couch-Beds, of which the following is a specification.

10 My invention relates to beds, of the form commonly known as "folding couch beds," and the object of such invention is to form a folding twin-bed of a new and improved, easily actuated, simple and cheap form of 15 construction, having twin spring-mattresses which have no connection with one another, whereby the operation of the same, when in use, is practically that of twin-beds, by reason of the fact that if two persons are occupying the bed, the weight of each, is exerted wholly upon the mattress on which each is lying; whereby the slipping to the center of the bed of the heavier person is absolutely prevented. And such bed, of my improved 20 form, can be quickly folded up, practically into the width of a single bed, without the removal of the hair or fiber mattresses, carried by such twin spring mattresses.

My said invention is fully shown, described and claimed in the following specification of which the accompanying drawing forms a part, wherein similar letters or numerals of reference designate like or equivalent parts wherever found throughout the 35 several views, and in which:

Figure 1, designates a folding twin-bed of my improved form, with the fiber mattresses removed, in the open position;

Fig. 2, is an end view of such bed, in the 40 same position in full lines, and in process of being opened or closed in dotted lines; and

Fig. 3, is an end view of the same in the closed position.

45 The main-frame of the bed, in this case the frame shown at the right of Fig. 1, comprising two end or head and foot frames 1 and 1', each consisting of the top-bars 2 and 2', and the leg-portions 3 and 3' depending therefrom, which are usually bent up from L shaped angle-iron, as clearly indicated at 2' of Fig. 1; which frames are cross-strengthened at the bottom by the like L shaped cross-pieces or bars 4 and 4', secured 50 to the legs 3 and 3', adjacent to the bottom

thereof, by the securing-bolts or pins 5 and 5', or in any other desired manner.

These head and foot supporting frames, of such right hand main-portion of the bed, are longitudinally secured together by the L shaped side-bars 6 and 6', the ends of which are usually inserted within the L of the head and foot-pieces 3 and 3', and bolted thereto by suitable bolts 7 and 7', or secured thereto in any other desired manner. This portion of my improved folding-bed or couch, for convenience of description, will be hereinafter termed the main-bed portion A, as it is not moved in folding and unfolding, and when folded, supports the movable-bed portion B, which differs from such main-bed portion A in having only outer leg-pieces 3" and 3'", on the outer ends of each of the top-bars 2 and 2'; and the inner ends, when in position, each rest upon a suitable support carried by the top-bars 2 and 2' of the main-bed portion A, at the adjacent side thereof, which are usually in the form of L shaped bracket-pieces 8, riveted or spot-welded, etc., to the top-bars; and the two legs 3" and 3'", are connected together, longitudinally, by an L shaped longitudinal bar 6", in like manner as the bars 6 and 6' connect the legs 3 and 3' of A.

Secured at either end to the central legs 3 and 3' of the main-bed portion A, by the pivot-bolts 5, and to the top-pieces or bars 2 and 2' of the secondary or auxiliary-bed B, by like pivot-bolts 5", are the rock-levers D; and pivoted at the end of the top-bars 2 and 2', of the auxiliary-bed portion B, by pivot-bolts 9, are the ends of the end-pieces E' of the elongated substantially rectangular L shaped rock-lever, which are also pivoted, adjacent to the bottom-bar E, to the cross-bars 4 and 4', by the pivot bolts 10; and such rock-lever, composed of E and E', is usually and preferably formed of steel tubing bent into rectangular elongated form. The bottom-bar E, extends within, and longitudinally of the main-bed portion A, as indicated in Fig. 1; and rests at all times upon two resilient spring-tensioning throw-plates 12, located within the main-bed portion A, at either end, usually of flexible spring-steel; secured at one end to the bar 6' of the main-bed portion A, by a coil-spring 11, and on the other end, to the bar 6, by a like coil-spring 13.

The throw plates 12 are each loosely

wrapped about the bottom bar E in a spiral manner.

When the bed is in the half open position, (dotted lines of Fig. 2) it will be seen that the bottom-bar E of the lever being at the center of the flexible throw-plate 12, the angle of the springs 11 and 13 will be the same; and that as such lever is forced farther to what is the right of Figs. 1, 2, and 10 3, when the bed is fully opened, as is shown in full lines in Figs. 1 and 2, the angle of the two springs 11 and 13 will have been exactly reversed.

It will be seen from an examination of Figs. 2 and 3, that the longitudinal bottom-bar E, always rests upon the center of the flexible resilient-spring throw-plate 12, and that such plate is thus always in substantially the same relative position to the lever, 20 while the springs 11 and 13 change from vertical to inclined, and vice versa.

Any suitable form of spring-mattresses or bed-springs may be used, but I prefer to use the form shown, wherein secured to the ends of the two woven-wire spring mattresses 14, and at the outer ends, to the top-pieces or bars 2 and 2', are a plurality of coil-springs 15, in this case five at each end; and these mattresses differ in no way from 30 the ordinary form of well-known construction, and, except in combination, form no part of my invention.

Preferably secured at the corners and side-centers thereof, in any desired manner 35 to each of such spring mattresses, is a fiber-mattress (not shown), laid and secured thereon when the bed is in the open position shown in Fig. 1. The bed clothing is then adjusted over both, and the bed is ready 40 for use. The outer covering is usually a more or less ornate bed-spread such as tapestry etc.; and when it is desired to fold the bed into the folded or couch form, the bed-clothing is folded over upon the mattress of 45 the main-bed portion A, and if desired, one or both pillows also placed thereon; or one or both may be provided with ornate slip-covers of the same design as the spread-cover. The auxiliary or movable bed portion B is then thrown back into the closed 50 position shown in Fig. 3, through the movement shown in dotted lines in Fig. 2; during which, as well as in the reverse opening movement, the pressure of the lever-bar E upon the spring supported plate 12, will ease the lift and also damp the auxiliary bed portion B against sudden drop. The bed having been thrown into the folded 55 position shown in Fig. 3, the tapestry or other ornate cover is then draped over and around the auxiliary movable bed-portion B and a day couch formed.

It is evident that many modifications in the construction of the several parts, as well 60 as the manner of combining the same, may

be made therein without departing from the scope of my invention.

I claim:

1. A bed comprising a rectangular frame main-bed portion having four legs and bottom end cross-bars connecting adjacent legs, an auxiliary movable bed portion, having two supporting feet on the outer side and having head and foot pieces with top bars adapted to be thrown into and out of position on to and back from the top of the main-bed portion, an elongated substantially L-shaped lever member the extending ends of which are pivotally secured to the top bars of the head and foot pieces of the auxiliary 80 movable bed portion and to the bottom end cross bars of the main-bed portion, a spring member secured to the main-bed frame on one side, a spring member secured opposite thereto, and a spring member secured to the top of the L-shaped lever member at either end, 85 which spring member is loosely secured to the bottom bar of the L-shaped lever so as to govern and control the auxiliary bed portion against too rapid movement in being moved off from and on to the main-bed portion.

2. In a device of the character described, the combination of a main frame; an auxiliary frame; a rock lever comprising a bottom bar and upturned end pieces fulcrumed to said main frame, and to said auxiliary frame; rock links disposed substantially parallel to said end pieces and pivoted at their upper ends to said auxiliary frame and 95 at the lower part to said main frame; throw-plates loosely secured to said bottom bar; and springs tensioned between the ends of the throw-plate and the main frame.

3. In a device of the character described, 105 the combination of a main frame; an auxiliary frame; a rock lever comprising a connecting bar and a pair of end levers pivoted respectively to the frames; resilient throw plates having their middle part 110 loosely spirally wrapped around said connecting bar, whereby laterally projecting yieldable end plates are provided; and coil springs tensioned between the free ends of said end plates and said main frame.

4. In a device of the character described, 120 the combination of a main frame comprising end frames and side bars; an auxiliary frame comprising end bars; a rock lever comprising a bottom bar and upturned end pieces intermediately fulcrumed to an intra-marginal part of said end frames, the free ends of said end pieces being pivotally secured near the inner ends of said end bars; rock links substantially parallel to 125 said end pieces and pivoted at their upper ends to an intermediate part of said end bars, and at their lower ends to said end frames; resilient throw plates having their middle part loosely secured to said bottom 130

bar; and coil springs tensioned between the free ends of said throw plates and said side bars.

5. In a device of the character described, 5 the combination of a main frame comprising end frames each provided with a horizontal cross bar spaced between the upper and lower parts thereof, and side bars connecting said end frames and disposed higher than said cross bars; an auxiliary frame comprising end top bars and outer corner supports; a rock lever comprising a horizontal bottom bar disposed lower than said cross pieces, and upturned end-pieces 10 intermediately pivoted intermediately of said cross-bars and having their free ends pivotally secured near the inner ends of

said top bars respectively; rock links disposed substantially parallel to said end pieces and pivoted at their lower ends near 20 the outer ends of said cross-bars and at their upper ends to an intermediate part of said end top bars; resilient throw plates, having their middle parts loosely spirally wrapped around intermediate parts of said bottom 25 bar whereby laterally projecting yieldable end plates are provided; and coil springs tensioned between the free ends of said end plates and said side bars.

BENJAMIN WEISS.
